Inventor:
Francis M. Barton
By Fred Gerlach Atty.

UNITED STATES PATENT OFFICE.

FRANCIS M. BARTON, OF CHICAGO, ILLINOIS.

CONCRETE REINFORCEMENT.

Application filed September 6, 1927. Serial No. 217,571.

The present invention relates to reenforcement for concrete, and more particularly to reenforcement of that character which is adapted for the concrete covering of the 5 structural metal beams or shapes.

The object of the invention is to provide an improved reenforcement which is made up of wires and which comprises longitudinal and cross-members which are disposed beneath the beam and are adapted to serve as 10 spacers for the bottom and sides of the form for the concrete.

Another object of the invention is to provide reenforcement of this character which 15 can be readily and easily applied to the beams and can be produced at a low cost.

The invention consists in the several novel features hereinafter set forth and more particularly defined by claims at the conclusion 20 hereof.

In the drawings: Fig. 1 is a sectional perspective illustrating the reenforcement applied to a beam, and before the concrete has been poured around it. Fig. 2 is a vertical 25 cross-section after the concrete has been poured into the form. Fig. 3 is a sectional perspective, illustrating a modified form of the invention.

The invention is exemplified in a reenforcement 30 comprising a pair of longitudinal wires a and a' which are spaced apart so as to underlie the marginal portions of the beam b . The longitudinal wires are provided with integral downwardly extending loops a^2 connected by intermediate upwardly extending loops a^3 . The upper ends of loops a^3 are adapted to 35 abut against the underside of the beam, and the lower ends of the loops a^2 are extended to properly space the bottom d of the form for the concrete from the bottom of the beam 40 for the concrete covering around the beam. The longitudinal wires are fixed to, and spaced apart by cross-wires c adjacent the upper ends of the loops a^3 , and the end portions c' of these cross-wires are normally 45 shaped to extend upwardly at the edges of the bottom flange of the beam, as indicated by dotted lines in Fig. 2, so they may be readily bent around the margins of the beam 50 flanges, to secure the reenforcement to the beam. Cross-wires e are secured to the longitudinal wires a, a' , so they will be spaced from the bottom of the beam and have their ends extended to properly space the sides d' of the 55 form for the concrete relatively to the beam,

to form the desired concrete covering around the sides of the beam. In practice, the cross-wires and longitudinal wires are preferably welded at their crossings. In the manufacture of the reenforcement, it is cut from strips 60 of fabricated material, so that the cross-wires will extend laterally, the desired distance from the beam, to serve as spacers. The longitudinal wires are then bent to form the spacing loops, and the cross-wires c are bent 65 to form the upstanding terminals. The reenforcement is thus formed in strips of the desired length, and in transportation, the strips are nested so they will occupy comparatively little space. 70

Figure 3 illustrates a modified form of the invention, in which the longitudinal wires a^{10} and a^{20} are adapted to lie immediately underneat the bottom of the beam, and are provided with downwardly extending loops 75 a^5 to space the bottom d' of the form from the bottom of the beam, and the reinforcing cross-wires e' are secured to the loop portions in spaced relation from the bottom of the beam. The retaining wires c are secured 80 to the portions of the longitudinal wires between the loops a^5 , and are adapted to be bent around the beam flanges as before described.

The invention exemplifies reenforcement 85 composed of a plurality of longitudinal wires and cross-wires which are adapted to reinforce the concrete below the beam to prevent it from splitting, and also to accurately space the bottom and sides of the form for 90 the concrete relatively to the beam. The reenforcement can be produced at a low cost, and easily and readily applied to the beam or structural shape which is to be covered with concrete. 95

The invention is not to be understood as restricted to the details set forth, since these may be modified within the scope of the appended claims, without departing from the spirit and scope of the invention. 100

Having thus described the invention, what I claim as new and desire to secure by Letters Patent, is:

1. In reenforcement for concrete, the combination of a plurality of wires adapted to extend longitudinally under a beam and having portions thereof bent downwardly to space the bottom of a form from the beam, cross-wires fixed to the longitudinal wires so as to be spaced away from the beam and to 105 110

reenforce the concrete under the beam, and means for securing the reenforcement to the beam.

2. In reenforcement for concrete, the combination of a plurality of wires adapted to extend longitudinally under a beam and having portions thereof bent downwardly to space the bottom of a form away from the beam, cross-wires fixed to the longitudinal wires so as to be spaced from the beam and to reenforce the concrete under the beam, and extended to space the sides of the form from the beam, and means for securing the reenforcement to the beam.
- 10 3. In reenforcement for concrete, the combination of a plurality of wires adapted to extend longitudinally under a beam and having portions thereof bent to space the bottom of a form from the beam, cross-wires fixed

so as to be spaced away from the beam and to reenforce the concrete under the beam, and cross-wires fixed to the longitudinal wires having the ends thereof connected to the intermediate or central portion by right angle bends and adapted to be bent around the beam for securing the reenforcement to the beam.

20 25 4. In reenforcement for concrete, the combination of a plurality of wires adapted to extend longitudinally under a beam, having integral loops to space the bottom of a form from the beam, cross-wires fixed to the longitudinal wires, so they will be spaced from the beam and to reenforce the concrete under the beam, and means for securing the longitudinal wires to the beam.

30 35 Signed at Chicago, Illinois, this 8th day of July, 1927.

FRANCIS M. BARTON.
